RECEIVER FOR PRINTING-TELEGRAPH SYSTEMS.

1,181,985.

Specification of Letters Patent.

Patented May 9, 1916.

Application filed July 10, 1913. Serial No. 778,256.

To all whom it may concern:

Be it known that we, CHARLES G. ASHLEY, a citizen of the United States of America, and a resident of Chicago, county of Cook, and State of Illinois, and ERNEST T. BYSHE, a citizen of the Dominion of Canada, and resident of Toronto, county of York, and Province of Ontario, Canada, have invented a new and useful Improvement in Receivers for Printing-Telegraph Systems, of which the following is a specification.

Our invention relates to automatic printing telegraph systems of the class using printing characters which, from the nature 15 of their making, may be termed composite characters and embodies a novel and improved receiver for use with such systems which utilize a novel and improved method of recording impressions on a recording surface.

It is with a view toward simplifying the mechanism and manufacture and obtaining infallibility and maximum efficiency of operation that our invention is directed. These 25 and other desiderata which will subsequently be disclosed herein, we accomplish by employing a magnetic field which normally maintains a series of armatures bearing hammers in a position which restrains 30 the hammers from contact with a receiving surface which lies between the hammers and a solid type block presenting adjacent to the under portion of the receiving surface, a type face composed of elemental character 35 components and further means to cause the hammer borne by any selected armature to strike said receiving surface to imprint thereon from said single type a selected portion of its type face.

In the figures which accompany and form 40 a part of this specification and in which like numerals designate corresponding parts throughout, Figure 1 illustrates in diagram a simple form of transmitter, our improved receiver and the conductors connecting them. Fig. 2 is a plan view of the printing type of our improved receiver. Fig. 3 is an elevation of the same. Fig. 4 is a side elevation of our receiver. Fig. 5 is a sectional view 45 of the same taken on the line A—A of Fig. 4. Fig. 6 is a section of transmitting tape perforated to send a few selected characters and record the same with our improved re-

ceiver. Fig. 7 is a section of receiving tape showing the outline of the selected characters as recorded by our improved receiver.

While we have presented at the left of Fig. 1 in diagram a simple form of transmitter, our improved receiver is adaptable to use with any type of transmitting mechanism provided this mechanism is designed to impress selectively upon the coils of the receiver, current impulses of variant polarity. The transmitter shown comprises two direct current dynamos 20 and 21 or other convenient sources of current, their terminals of opposite polarity being connected together and to ground 22 while the negative terminal of dynamo 21 is connected to brushes 18' and 18² and the positive terminal of dynamo 20 is connected to brushes 18² and 18⁴. A brush 15 is connected to line conductor 40 and is of sufficient width to bear upon both brushes 18' and 18² and make contact therewith while a brush 16 is connected to line conductor 41 and is of sufficient width to bear upon brushes 18³ and 18⁴ and make contact therewith. Brushes 15 and 16 are, however, normally held out of contact with their respective pair of brushes 18' 18² and 18³ 18⁴ by means of a transmitting tape 17 through perforations in which contact may be selectively made between any brush of a pair of brushes as 18' and 18² with their respective line brushes as 15 and 16 to send selectively over either line conductor 40 or 41 and ground, negative or positive impulses as required. The transmitting mechanism thus constitutes a simple means for selectively transmitting to the receiver coils, current impulses of variant polarity.

Our improved receiver, the line connections of which are indicated in diagram at the right of Fig. 1 and the mechanism in more detail in Figs. 2 to 5 inclusive, comprises a permanent magnet 35 of the form shown in Fig. 4. A series of bell-crank-shaped armatures 10', 10², 10³ and 10⁴ which may be formed of either iron or steel are pivoted by means of a pin 37' in a series of slots cut in a brass-supporting member 37 which is attached by screws as indicated to one pole face of the permanent magnet 35. The other pole face of the permanent magnet is beveled to an edge which lies in the plane of the axis of rotation of the arma-

tures 10^1 — 10^4 while each of the extremities of the arms of the armatures that extend substantially across the air gap of the permanent magnet are beveled to an edge which likewise lies in the same plane as the axis of rotation of the armatures. A small hammer is borne as an integral part thereof upon each extremity of the extended portions of the armatures 10^1 — 10^4 and the extended portions or arms of the armatures are bent to bring their respective hammers into such relation to each other as that shown in Fig. 5. The printing type 30 shown in Figs. 2 and 3 is placed adjacent to all of the hammers and is adjustable in its distance therefrom by means of a screw 30⁵. This printing type is preferably made from one solid piece of metal and presents to the under surface of a recording tape a series of type faces 1, 2, 3, and 4 grouped to form a printing symbol as shown in Fig. 2. The type faces are cut in relief in the block 30 and are disposed in a definite relation to each other as will be hereinafter fully described.

A pair of guides 30¹ and 30² are rigidly attached to the upper surface of the type block 30 as indicated and serve to guide an inked ribbon 140 in its longitudinal travel over the type faces 1, 2, 3 and 4 and to normally maintain it from contact with the type faces. An additional pair of guides 30³ and 30⁴ are formed as an integral part thereof of the guides 30¹ and 30² respectively and serve to guide the recording tape 141 and normally maintain it out of contact with the inked ribbon 140. The type block 30 bearing the type faces 1, 2, 3 and 4 and the guides 30¹, 30², 30³ and 30⁴ may be adjusted in its distance from the hammer armatures 10^1 — 10^4 by means of a screw 30⁵, as hitherto mentioned.

A series of electromagnets 31, 32, 33 and 34 are rigidly held in a brass apron 36 which is in turn attached to the upper pole face of the permanent magnet 35 by means of screws as 36¹. The electromagnets 31—34 are so placed in the apron 36 and the apron is so placed on the permanent magnet 35 that the poles of the electromagnets 31—34 are maintained opposite and slightly removed from their respective hammer armatures 10^1 — 10^4 . Thus they are so positioned as to produce adjacent to their associated hammer armatures when energized a magnetic field which is substantially at right angles to the polarizing field produced by the magnet 35.

The beveled pole face of the magnet 35 and the pointed extremities of the armatures 10^1 — 10^4 serve to concentrate all the magnetic flux into substantially a line which lies in the axis of rotation of armatures and as the apex of the printed extremities of the armatures lies in the axis of their rotation,

they are normally maintained in a definite position which restrains the hammers which they bear from contact with the recording surface.

Referring now especially to Fig. 1 it will be observed that the windings of electromagnets 31 and 32 are connected in series and to line conductor 40 and ground 23 and that electromagnets 33 and 34 are likewise connected in series and to line conductor 41 and ground 23. Electromagnets 31 and 32 are so wound that when energized by the passage of electric current through their helices unlike magnetic poles are manifested on their core extremities. Similarly electromagnets 33 and 34 are so wound as to present unlike magnetic poles upon their core extremities when energized by the passage of current through their helices; thus we will assume that a positive impulse of current over line conductor 40, electromagnets 31 and 32, to ground produces upon the pole face 31¹ (Fig. 5) of electromagnet 31, a N. magnetic pole and an S. pole on the pole face 31². However, as the upper extremity of the hammer armatures 10^1 — 10^4 are polarized to present S. magnetic poles as indicated by the lettering on the permanent magnet 35, it is evident that there has been created adjacent to the S. pole of armature 10^1 a N. magnetic pole which is substantially at right angles to the polarizing field and hence the armature attempts to place itself in the field resultant from the two component fields and thereby causes the hammer which the armature bears to exert pressure on the receiving tape 141 and inked ribbon 140, over a particular portion of the type face of the type block 30, as indicated by the dotted outline and dotted index designated by the numeral 10¹ in Fig. 2, thus causing an impression of type face 1 to be recorded on the under surface of the receiving tape 141. This same current impulse over line 40 through electromagnets 31 and 32 which produces a N. magnetic pole upon the pole face 31¹ of electromagnet 31 also produces an S. magnetic pole upon the pole face 32¹ which as the armature adjacent thereto, 10², is polarized to have an S. magnetic pole upon its upper extremity, the armature tends to rotate to assume a position in the field resultant from the polarizing field and the newly created repelling field and the hammer which the armature bears is thus lifted farther from the receiving tape and an impression of type 2 is not recorded. A negative impulse of current over line conductor 40 through the helices of electromagnets 31 and 32 produces a N. magnetic pole on pole face 32¹ of electromagnet 32 which results in imprinting an impression of type face 2 as hitherto explained. Further a positive impulse of current over line conductor 41 through electromagnets 33 and 34 produces a N. magnetic

5 pole on pole face 34¹ to record an impression of type face 4 while a negative impulse of current over the same line conductor and through the same electromagnets produces a 10 N. magnetic pole on pole face 33¹ to record an impression of type face 3; thus by means of impulses transmitted over the line conductor 40 and 41 through electromagnets 31, 32, 33 and 34 in predetermined pairs any 15 type face of the group presented by the type block 30 may be selectively recorded on the receiving tape dependent upon which line conductor the impulses traverse and upon the polarity of the impulses.

15 A transmitting tape 17, a portion of which is shown in Fig. 6 is used to select the proper line conductor and polarity of impulse to correctly build up the impressions from the elemental type faces to form legible roman 20 characters. On the tape the perforations are spaced longitudinally along four transversely spaced rows 19¹, 19², 19³ and 19⁴ corresponding to the lines of contact of the 25 brushes 18¹, 18², 18³ and 18⁴ respectively with the brushes 15 and 16. Thus a perforation in the tape on line 19¹ allows contact to be made between brush 18¹ and brush 15 to transmit from the negative terminal 30 grounded dynamo 21, a negative impulse of current over line conductor 40, through electromagnets 31 and 32 to ground, to imprint as hitherto described an impression of type 35 face 2; similarly perforations in the tape spaced longitudinally on the lines 19², 19³ and 19⁴ allow current impulses of the proper potential to traverse the proper line conductor to imprint type faces 2, 3 and 4 respectively.

40 It remains now to disclose the method of building up the impressions from the type faces to form legible characters.

45 Referring to Fig. 2 which illustrates the type faces as they are grouped in the single type block 30, it will be observed that the faces 1, 2, and 3 are each in width equal to the width of a complete normal character, such as "H" and that this width is divided into four equal units; each of the type faces being separated from its adjacent type face 50 by one of these units of width to form the printing symbol. The longitudinal spacing of the perforations on the transmitting tape 17 is dependent upon the ratio between the speed of the transmitting and receiving tapes and is such that while the receiving tape moves one unit of width of a complete normal character as imprinted by the printing symbol, the transmitting tape moves a distance equal to the distance between any two 55 transverse lines thereon.

60 The character "A" is transmitted and recorded as follows: Conceive the transmitting tape 17 perforated as shown in Fig. 6 to move from right to left as viewed in the

figure between the brushes 18¹—18⁴ and 15 65 and 16 of the transmitter of Fig. 1 at a speed which allows one transverse spacing of the tape or one tape interval to pass the contact line of the brushes while the receiving tape 141 is being drawn from right to left 70 over the type faces of Fig. 2 or as shown by the direction of the arrow in Fig. 5, a distance equal to one unit of width of a complete normal character. Then a perforation in the transmitting tape spaced on the line 75 19⁴ allows of contact being made between brush 18⁴ and brush 16 to transmit from dynamo 20 over line conductor 41 through electromagnets 33 and 34 to ground, a positive 80 impulse of current which operates hammer armature 10⁴ to record an impression of type face 4 upon the under surface of the receiving tape 141. After the transmitting tape has moved eight tape intervals and the receiving tape has moved eight units of 85 width of a normal character, a perforation in the transmitting tape spaced on the line 19⁴ again allows contact to be made between brushes 18⁴ and 16 to send a positive impulse of current over line conductor 41 through 90 electromagnets 33 and 34 to ground to again imprint type face 4 upon the receiving tape a distance away from the previous impression which is equal to the width of a complete 95 normal character. When the transmitting tape has moved two additional tape intervals a perforation in the tape on the line 19² allows contact to be made between brushes 18² and brush 15 to send a positive impulse of current from dynamo 20 over line conductor 40 through electromagnets 31 and 32 which imprints an impression of type face 100 2, and as the receiving tape 141 has since the last impression of type face 4, moved a distance equal to two units of width of a normal 105 character, the impression of the type face 2 falls with its two extremities in contact with the middle portions of the two previous impressions of type face 4. After the transmitting tape has moved an additional 110 tape interval during which time the receiving tape has also moved one unit of width of a normal character, a perforation in the transmitting tape placed on the line 19¹ allows a negative impulse of current to 115 be sent over line conductor 40 through electromagnets 31 and 32 to record an impression of type face 1; this impression falls with its free horizontal extremity in contact with the upper extremity of the last 120 made impression of type face 4 while the vertical leg of the imprint of type face 1 registers with the upper half of the first impression of type face 4 to form the character "A". Similarly all of the characters 125 of the alphabet and the numerals from 0 to 9 may be built up and recorded as shown by the few selected characters of Fig. 7.

4

It will be observed from the foregoing that the type faces are cut in relief in a solid type block, that they may be accurately positioned with respect to each other and that this position may be at all times maintained; further that the hammers are in effect small platens individual to their particular type faces and that thus an evenly distributed and uniform pressure is obtained between any type face and its associated platen to accomplish an even distribution of the ink in the impression derived from the type face.

While we have disclosed but one embodiment of our device it should be clearly understood that we may make numerous changes in the details thereof, without departing from the spirit or narrowing the scope of our invention.

Having thus described our invention what

we claim as new and desire to secure by United States Letters Patent, is as follows:

In a printing telegraph receiver, a receiving surface, a type block maintained rigidly out of contact with said receiving surface, said type block presenting in relief type faces comprising elemental character components which constitute an illegible monogram, and means for bringing portions of said receiving surface selectively against 25 said type faces to affect the impression of said type faces.

Signed by us at Toronto, county of York and Province of Ontario, in the presence of two witnesses.

CHARLES G. ASHLEY.
ERNEST T. BYSHE.
